DRIPPROOF CUP

Floyd M. Cockriel, Edgerton, Mo.

Application July 3, 1950, Serial No. 171,979

5 Claims. (Cl. 65—13)

1

My invention relates to a drip-proof cup.

A primary object of the invention is to provide a cup having means to prevent it from running over due to over-filling or shaking of the cup, and thereby eliminating the usual annoying accumulation of drippings in the saucer upon which the cup is seated.

A further object is to provide a cup equipped with absorbent means which prevent drippings from running down the outside of the cup and accumulating in the saucer beneath the cup.

A further object is to provide a non-drip cup of the above mentioned character which is highly simplified in construction, neat and attractive in appearance, sanitary, wholly practical and inexpensive to manufacture.

A further object of the invention is to provide a drip-proof cup having a novel overflow passage communicating with an absorbent element, so that the cup cannot readily spill over, the drip-proof cup being particularly useful on moving trains and the like, where it is liable to be constantly shaken or agitated.

Other objects and advantages of the invention will be apparent during the course of the following description.

In the accompanying drawings forming a part of this application, and in which like numerals are employed to designate like parts throughout the same,

Figure 1 is a side elevational view of a drip-proof cup embodying my invention, parts in section; and

Figure 2 is a horizontal sectional view taken on line 2—2 of Figure 1.

In the drawings, where, for the purpose of illustration, is shown a preferred embodiment of my invention, the numeral 10 designates a saucer upon which rests a drip-proof cup 11 embodying the invention. The cup 11 comprises a flat bottom 12 and an upwardly flared, conical side wall 13 integral therewith. The cup is provided at its bottom with a narrow, external, annular flange 14 integral therewith, and the cup has the usual, radially extending, apertured handle 15 near its open top.

The cup is provided in its side wall 13 at diametrically opposite points with narrow, elongated overflow passages 16 extending from points near and below the top of the cup to points substantially at the vertical center thereof. As best shown in Figure 2, one of the overflow passages 16 is disposed adjacent to the handle 15. At their top ends, the generally vertical overflow passages 16 open through the inner surface of

2

the side wall 13, as at 17, preferably about one-quarter of an inch below the top of the cup, although this distance may be varied if desired. The bottoms of the overflow passages 16 open radially through the outer surface of the side wall 13, as at 18, substantially at the vertical center of the cup.

A flexible, highly absorbent band or ring 19 of sponge rubber or the like surrounds the side wall 13, and snugly engages the same as shown. The band 19 extends continuously about the side wall of the cup and has its bottom end seated upon the annular flange 14. The band 19 extends from the bottom of the cup to a point near and above the bottom discharge openings 18 of the overflow passages, so that the discharge openings are completely covered by the band when it is applied to the cup. The absorbent band 19 preferably gradually increases in thickness throughout its entire height and toward its top edge. At its bottom, the periphery of the band 19 is preferably flush with the periphery of the annular flange 14, as shown. The top edge of the band 19 is preferably slightly hollowed or concave, as at 20, for a reason to be explained. As shown clearly in Figure 1, the major portion of the band 19 extends below the discharge openings 18 of the overflow passages 16, so that the band may absorb a maximum quantity of the liquid overflowing through the passages 16. Because of its elasticity, the band 19 is readily removable over the flange 14, so that the cup and band may be washed and dried separately.

In use, when the cup 11 is filled with coffee, tea or the like, and when the surface of the liquid reaches the level of the top openings or entrances 17, the liquid will begin to overflow through the passages 16, which convey it to the absorbent band or ring 19. Accordingly, if one tends to overfill the cup, instead of its spilling over and running down into the saucer 10, the excess liquid is conveyed directly by the passages 16 to the absorbent band. Also, when the cup is raised to the lips by means of the handle 15, its side remote from the handle is usually raised or tilted upwardly, and when this occurs, instead of the liquid overflowing the side of the cup adjacent to the handle, it will enter the overflow passage 16 nearest the handle and be conveyed to the absorbent band. By arranging the handle 15 adjacent to one of the overflow passages, such passage will function as just described, regardless of whether a right or left-handed person elevates the cup by the handle.

If the cup is shaken or agitated to such an

extent that the overflow passages 16 cannot convey all of the liquid to the band 19, and some of the liquid does overflow the brim of the cup, such liquid will run down the outer surface of the side wall 13 and into the concave, top edge 20 of the band 19, where it will be quickly absorbed by the band. Likewise, when the cup is elevated to the lips for drinking, any drippings left on the outer surface of the side wall 13 will run down the side wall to the concave, upper edge 20 and be absorbed by the band.

My drip-proof cup is particularly desirable on moving vehicles, such as trains, where the dishes are subject to constant shaking or agitation. Likewise, my cup should be highly desirable in restaurants and in the home, since it tends to eliminate entirely the annoying drippings which generally accumulate in the saucer, so that when the cup is raised, some of the drippings adhere to its bottom, and then run off onto the clothes, tablecloth, or the like. Further, the annoying condition created by the drippings in the saucer, whereby the saucer tends to stick or adhere to the bottom of the cup, is eliminated. Since the band 19 is readily removable, as previously stated, the arrangement is sanitary and the cup and band may be separately washed and dried. The band 19 in no way interferes with the normal use of the cup, and the arrangement is compact and neat and attractive in appearance.

It is to be understood that the form of the invention herewith shown and described is to be taken as a preferred example of the same, and that various changes in shape, size and arrangement of parts may be resorted to without departing from the spirit of the invention or the scope of the subjoined claims.

Having described the invention, what is claimed as new is:

1. A drip-proof cup including a side wall provided with a generally vertical overflow passage having an inlet end opening into the interior of the cup near and below the top of the cup, the overflow passage having an outlet opening opening through the outer surface of the side wall near the vertical center of the cup, and an annular absorbent band mounted upon and surrounding the side wall of the cup and extending from a point near the bottom of the cup to a point near and above the discharge opening and covering the discharge opening so as to absorb liquid flowing from the overflow passage.

2. A drip-proof cup including a side wall pro-

vided with an overflow passage having an inlet opening near and below the top of the cup and a discharge opening near the midportion of the height of the cup and leading through the outer face of the side wall, and an absorbent band mounted upon the side wall and covering the discharge opening and extending from a point near and above the discharge opening to substantially the bottom of the cup, the top of the band projecting radially of the side wall for a substantial distance so that liquid running down the outer face of the side wall will meet the top of the band and be absorbed by the band.

3. The combination of claim 2 wherein said band has an upstanding peripheral edge to enclose a collecting basin upon the upper edge of the band surrounding the wall of the cup.

4. The combination of claim 2, said side wall having an external shoulder supporting the lower edge of said band.

5. The combination of claim 2, wherein said band has an upstanding peripheral edge to enclose a collecting basin upon the upper edge of the band surrounding the wall of the cup, said side wall having an external shoulder supporting the lower edge of said band.

FLOYD M. COCKRIEL.
